ADJUSTABLE KEY FOR LOCKS

Kalju Helenurm, Willowdale, Ontario, Canada, assignor
to Jonathan Lock Limited, Toronto, Ontario, Canada

Filed Jan. 15, 1973, Ser. No. 323,797

Term of patent 14 years

Int. Cl. D8—07

U.S. Cl. D8—136

FIG. 1

FIG. 2

FIG. 3

FIG. 1 is a perspective view of an adjustable key for locks embodying my design, viewed obliquely from one side;

FIG. 2 is a top plan view of the key; and

FIG. 3 is a perspective view of the adjustable key viewed obliquely from the other side of the key.

I claim:

The ornamental design for an adjustable key for locks, as shown.
